Attorney.

UNITED STATES PATENT OFFICE

2,370,696

PIN FOR TEMPORARY FASTENING OF
BUTTONSThea Stumpf, Frankfort-on-the-Main, Germany;
vested in the Alien Property CustodianOriginal application March 23, 1939, Serial No.
263,662. Divided and this application October
2, 1940, Serial No. 359,453. In Germany Febru-
ary 11, 1937

3 Claims. (Cl. 24—150)

This invention relates to improvements in pins to be used for the temporary fastening of buttons when fitting or trying on various articles of wearing apparel.

In United States patent application Serial No. 263,662, filed March 23, 1939, of which the present application is a division, there are disclosed pins to be used for temporary fastening of buttons when fitting or trying on various articles of wearing apparel.

It is most important, when trying on an article of wear, to first temporarily fix the buttons belonging to it perfectly in the desired position, and in such a manner that they can easily be removed and replaced by other buttons of a different shape if necessary. By this means the choice of the most suitable button is greatly simplified, and the same can then be sewn on in the exact position required, when the fitting is finished.

The temporary fastening and easy changing of buttons, when trying on or fitting articles of wearing apparel, is the aim of this invention, which is in the form of a pin with a shaft bent at the upper end in rectangular form, with a catch for a button with two or more holes, the buttons thus temporarily fixed being intended to be sewn afterwards, in the usual manner, on the article of dress in question.

For a more complete understanding of the invention there will now be described, by way of example only and with reference to the accompanying drawing, several forms of temporary fastening according to the present invention.

In this drawing:

Fig. 1 represents a side elevation of the pin of this invention, showing the temporary fastened button with holes;

Fig. 2 is a side elevation of the invented pins for fastening a button with four holes and

Fig. 3 is a perspective view of the pin following Figs. 1 and 2.

The pin 1, as shown in Fig. 1, is intended to

temporarily fasten two-hole buttons B, when trying on articles of wearing apparel. The upper end 2 of the shaft of the pin 1 is bent in rectangular form, and is provided at the end of this with a suitably constructed catch 9, see Fig. 3, which keeps the button B with the two holes temporarily in position after the pin has been stuck into the material in the usual way.

When a button has four holes C, the shaft of the pin 1 can be provided with two catches at different angles to each other, or two pins, 1—2—9, can be used to temporarily fasten a button with four holes C.

I claim:

15. 1. A fastener for temporarily securing perforated buttons to fabrics and the like, comprising an elongated pin having a pointed end portion for penetrating the fabric, an intermediate length for fitting into a button perforation, and a flat-
tened relatively wide opposite end portion lying in a plane disposed substantially at right angles to the plane containing said intermediate length and end portion, said intermediate length ex-
tending from the edge of said flat end portion in
20 a direction substantially normal to the plane of said end portion, and said pointed end portion extending at substantially right angles from the projecting end of said intermediate length, whereby one face of said button will be confined on said
25 intermediate length by said flat end, and the other face will be confined by said pointed end portion.

30 2. A fastener according to claim 1 wherein said end portions project substantially in opposite di-
rections from the opposite ends of said interme-
diate length.

35 3. A fastener according to claim 1 wherein said end portions project substantially in the same direction from the opposite ends of said inter-
mediate length.

40 THEA STUMPF.
